UNITED STATES PATENT OFFICE.

MICHAEL LIPTAK, OF ST. PAUL, MINNESOTA, ASSIGNOR TO LIPTAK FIRE BRICK ARCH CO., OF MINNEAPOLIS, MINNESOTA, A CORPORATION OF MINNESOTA.

FIRE ARCH.

Application filed December 15, 1920. Serial No. 431,036.

To all whom it may concern:

Be it known that I, MICHAEL LIPTAK, citizen of the United States, residing at St. Paul, in the county of Ramsey and State of Minnesota, have invented certain new and useful Improvements in Fire Arches; and I do hereby declare the following to be a full, clear, and exact description of the invention, such as will enable others skilled in the art to which it appertains to make and use the same.

My present invention relates to furnaces such as used in connection with boilers in steam generating plants, in steel plants, in 15 glass factories, and various other places, and is directed particularly to the provision of an improved fire arch structure therefor.

The present invention is in the nature of an improvement on or modification of the 20 fire arch disclosed and claimed in my pending application Serial Number 419,973, filed October 27, 1920, and it involves highly important novel features which make the present arch a very decided improvement over 25 said earlier form. In said earlier form of the arch, as a decided improvement over the art then known, the blocks of the arch were detachably and individually supported, so that, from a broad point of view, they were 30 independently replaceable, but no means was disclosed whereby this replacement could be made from the top of the arch or from the exterior of the furnace.

My present invention provides extremely 35 simple and efficient construction which makes it not only possible but an easy matter to independently replace defective or burned away blocks, by inserting the new blocks through the arch from the top thereof or from that side of the arch that is not exposed to the flames. This is highly important because it makes it possible and practicable to repair furnace arches without putting out the fire and, in fact, without 40 disturbing the fire.

The present improved arch is illustrated in the accompanying drawings, wherein like characters indicate like parts throughout the several views.

Referring to the drawings:

Fig. 1 is a fragmentary perspective showing the improved arch:

Fig. 2 is a perspective showing two of the bull-nose or corner-forming blocks of the 55 arch:

Fig. 3 is a fragmentary longitudinal section of the arch;

Fig. 4 is a front or inner end elevation of the arch, some parts being in transverse section some of the corner blocks being omitted;

Fig. 5 is a bottom plan view showing a portion of the arch;

Fig. 6 is a perspective showing the form of arch block that may be primarily used in 65 first building the arch;

Fig. 7 is a view corresponding to Fig. 6, but showing the two-section block that is used in making replacements;

Fig. 8 is a fragmentary transverse section 70 showing the two-part or sectional blocks, such as illustrated in Fig. 7 applied in the arch;

Fig. 9 is a bottom plan view showing an arch, the body of which is made up of the 75 two-part or sectional blocks;

Fig. 10 is a view in perspective corresponding to Fig. 7, but illustrating a still, further modified form of arch-forming 80 block;

Fig. 11 is a view corresponding to Fig. 3, but showing an arch having the blocks illustrated in Fig. 10 incorporated therein; and

Fig. 12 is a transverse vertical section 85 showing a portion of the arch illustrated in Fig. 11, some parts being broken away.

The preferred construction illustrated in Figs. 1 to 9, inclusive, will first be described. The fire arch is supported from the transverse main beams 13, as shown three in 90 number, and preferably in the form of I-beams, the ends of which are imbedded in the masonry side walls 14. Slidably hung on the lower flanges of the main beam 13 are beam hangers 15 having inturned upper 95 prongs that embrace the lower flanges of said beams, and having T-shaped channels in their lower portions formed by laterally spaced flanges with inwardly projecting opposing bearing bosses 16.

The beam hangers 15 are aligned on the several main beams 13, so that short longitudinally spaced upper flanges 17, of laterally spaced supplemental arch beams 18, are adapted to be slid into the channels and 100 rested on the bosses 16 of the aligned beam hangers 15. By the bosses 16, the supplemental beams 18 can be supported either in oblique or horizontal position. The supplemental or arch beams 18 and beam hangers 110

15 are preferably of cast iron, while the main beams 13 are preferably of commercial rolled steel.

At their lower edges, the supplemental beams 18 have outstanding flanges extending the full length thereof. The preferred form of arch-forming block for use in first constructing the arch, is shown in detail in Fig. 6 and it comprises a body portion 19 and a flanged head 19^a. The body 19 is rectangular in form and, at one side thereof, the flanged head 19^a projects laterally, while at the other side, said body projects far beyond the adjacent flange of said head, but leaves an undercut shoulder at 19^b. The flanged head of this block is wide enough to span the space between adjacent supplemental beams 18 and to rest upon the lower flanges thereof. The lateral dimension of the body portion 19 is such that when the block is hung on the beams 18, as stated, its offset side will underlie one of the supporting beams and will be aligned approximately with the far edge of the overlying beam. Blocks of the kind just described are adapted to be readily slid on the beams 18, to proper positions in the first construction or erection of the arch, but are not adapted to be used in replacing defective blocks without removing adjacent blocks, because they cannot be inserted downward through the arch from the top thereof.

The block shown in detail in Fig. 7 is of the same construction as that shown in Fig. 6, except that it is made in two parts 19^c and 19^d by splitting or dividing said block at 19^c, and this divided block is especially adapted for use in replacing defective or burned away blocks. In this divided block, the widest section 19^c is narrow enough to pass between the flanged beams 18 and, hence, may be placed in position and hung on the flange of a beam 18, first by a downward, then by a lateral movement, which latter movement will place the offset side of the block under the beam and the shoulder 19^b on the flange of the beam. Then, when the block section 19^d is forced downward to position best shown in Figs. 1 and 8, its flanged head will rest on the lower flange of the other supporting beam 18 and the two block sections will then be assembled very much the same as if they were a single block, and both block sections will be interlocked to the supporting beams.

Of course, before one or more of these two section blocks can be applied as described to replace a defective block of the character shown in Fig. 6, the underlying block or blocks 19 must first be driven through the arch and downward into the furnace. All these operations may be easily performed by a person working on or above the arch. In Fig. 1, one of the arch blocks is left out and may be assumed to have been driven

down through the arch. The arch shown in Fig. 1 is illustrated as made up chiefly of the one-piece block 19, but in several instances, the two-piece blocks 19^c—19^d are shown as applied in the arch. Of course, the entire arch, or substantially the entire body portion thereof, may be made up entirely of the two-piece or sectional block.

In the preferred manner of applying the arch blocks, the offset sides thereof are alternately projected in adjacent rows, that is, the blocks of one transverse row will be projected toward the right, the next toward the left, the next toward the right, and so forth, so as to produce offsets or broken lines in the joints between the blocks in a direction longitudinally of the arch or in the direction in which the flames move in contact with the arch.

In the construction illustrated, the supplemental beams 18 are made in sections and connected by telescoped flanges and socket arms 20, which latter have T-shaped longitudinal channels and are preferably formed as inner end extensions of the respective beam sections.

At the inner ends of the inner sections of the beams 18 are detachable beam tips 21 that have the same general cross section as the beams and have end flanges that are slid into the socket arms 20 of the inner beam sections.

These beam tips 21 support metallic crown plates 22, on which an apron wall 23 is built. The apron wall is thus supported in a position above the top of the blocks 19, so that the latter may, when desired, be slid on the beams either to or from working positions.

To finish the inner end of the arch and form what is generally known as bull-nose, I provide corner blocks 24, (see Figs. 1 and 2). These blocks 24 are arranged to fit in pairs between the beam tips and are formed with undercut shoulders 24^a to rest on the lower flanges of the beam tips 21. Inward of the beam tips, the blocks 24 are formed complete or intact so that they protect the metallic beam tips from the flames, and said blocks are also formed with upstanding ribs 24^b that protect the metallic crown plates 22. Fig. 9 shows the body of the arch as made up of sectional blocks 19^c—19^d and corner blocks 24.

Figs. 10, 11 and 12 show an arch block that is of a type more fully disclosed and claimed in my prior application above identified, but differs therefrom in the fact that it is made up of two sections, adapting the block to be placed in position from the top of the arch or, in other words, from the relatively cold side thereof. This form of block comprises a body or main section 25 and a supplemental section 26, said sections, respectively, having undercut heads 25^a and 26^a.

The body 25 is offset at one side from its head 25^a, so that the offset portion will underlie one of the beams 18. In the other directions, the heads 25^a and 26^a are narrower than the body sections, so that flat hanger bars 27 can be inserted in position under said heads while their ends are resting on the lower flanges of the beams 18, (see Figs. 11 and 12). These views, Figs. 11 and 12, show how the blocks 25—26 are independently hung from the beams 18. It is evident that when the hanger bar 27 is slid out from under the heads of the block sections 25 and 26, the latter will drop from the arch into the furnace. In applying these sectional blocks in position from the top of the arch, the block sections 25 must, of course, be first positioned and then the block sections 26 positioned and the two block sections hung on a bar 27, as indicated.

The following further observations are also pertinent: The block sections, when assembled, form a composite block, the width of which equals the distance between supporting beams 18 measured from center to center of beams. The transverse width of the block sections 19^a and 25 is slightly less than the distance between the flanged lower portions of the beams 18, so that said block sections will pass freely between the beams. As preferably constructed and shown, the block sections 19^a and 26 are of approximately the same width as the lower flanges of the beams 18. When the block sections are hung in position, the offset side of the block section 19^a or 25, as the case may be, is approximately vertically aligned with the far flange edge of one of the supporting beams

and the block section 19^a or 26, as the case may be, will be approximately vertically aligned with the near flange edge of the other supporting beam. With this arrangement, therefore, the block sections 19^a and 26 may be moved vertically to or from working position, by an operator at the top of the arch, for the reason that it has no part that underlies any beam or any block section and therefore acts as a sort of a key or retaining block.

The advantages of being able to repair furnace arches or the like by an operator at the top or cold side thereof are, of course, very great, but are so obvious to those familiar with the subject that no extended comment is here deemed necessary.

What I claim is:

1. A fire arch comprising laterally spaced beams and arch-forming blocks hung from said beams and having body portions that are laterally offset so that one side is approximately vertically aligned with the far edge of one of said supporting beams and the other side of said block is approximately vertically aligned with the near edge of the other supporting beam, said blocks having head flanges that overlap and directly engage the two adjacent supporting beams, the joints between said end blocks being staggered or offset in respect to the joints between the adjacent arch-forming blocks.

2. The structure defined in claim 1 in which the blocks in adjacent transverse rows have their offset portions alternated so as to form broken or offset joints.

In testimony whereof I affix my signature.
MICHAEL LIPTAK.
